UNITED STATES PATENT OFFICE.

ROBBIE GORDONE, OF NEW YORK, N. Y.

HAIR-CURLER.

1,383,099.

Specification of Letters Patent. Patented June 28, 1921.

Application filed November 24, 1920. Serial No. 426,268.

To all whom it may concern:

Be it known that I, ROBBIE GORDONE, a citizen of the United States, and resident of the city of New York, county and State of New York, have invented certain new and useful Improvements in Hair-Curlers, of which the following is a specification.

My invention relates to hair curlers and more particularly to a device of this type which embodies a member upon which a lock of hair is adapted to be wound and held in place by a resilient member hinged to the hair receiving member.

The device is particularly adapted to cause the hair to assume a wavy appearance which is particularly desirable in a lady's coiffure.

In accomplishing this result I form the curler which comprises my invention in two sections. One of these sections is dished or channel-shaped in cross section and is comparatively rigid and upon this member a lock of hair is adapted to be wrapped. The second member is a resilient strip hingedly secured to the member upon which the hair is wound and is adapted to be sprung toward the hair receiving member to secure the hair thereon. The transverse dimension of the resilient member is somewhat less than that of the rigid hair receiving member and when in closed position this resilient member causes the hair to lie against the channel-shaped wall of the hair supporting member which causes the desired wavy effect.

The structure of my improved curler will be made more apparent in the accompanying specification and drawings in which:

Figure 1 is a perspective view of the curler in open position,

Fig. 2 is an end elevation thereof,

Fig. 3 is a side elevation,

Fig. 4 is a top plan view,

Fig. 5 is a bottom plan view and

Fig. 6 is an enlarged cross sectional view with a lock of hair confined between the parts of the curler.

The curler comprises two sections, or arms A and B. The section A is comparatively rigid and shaped into concavo-convex form in cross section as clearly illustrated in Figs. 2 and 6. The free end of the arm A is indicated by the numeral 10 while the opposite end is provided with a slot 11. The concavo-convex arm A is so positioned with respect to the arm B that its concaved face 12 is adjacent the arm B.

The arm B is in the form of a flexible strip which carries at one end thereof a tongue 13 adapted to pass through the slot 11 and be bent as illustrated in Fig. 1 to form a hinged connection between the two arms. The arm B is bowed longitudinally and has its free end bent right-angularly to form a lip 14 and provided with a projection 15 formed preferably by depressing the lip 14 at a point opposite the projection. When the arm B is sprung in the closed position adjacent the arm A the free end 10 of arm A is adapted to be secured by the projection 15 clearly illustrated in Fig. 3. The width of the flexible arm B is somewhat less than that of the concavo-convex arm A so that when the arms are sprung into closed position the arm B will be partially confined within the channel formed by the concaved face of the arm A. This will cause the lock of hair to assume more closely the contour of the concaved face 12.

In using my improved curler the lock of hair which is indicated at K in Fig. 6, is wrapped around the concavo-convex member and thereafter the resilient arm B is sprung into closed position. In this position the lock of hair is made to lie adjacent and follow closely the contour of the concavo-convex member and particularly the concave face thereof. With the hair thus confined along the concave face of the member A, it is caused to puff around the edges of the arm A as indicated at L in Fig. 6. This puffing of the hair as indicated at L is occasioned because of the change in the symmetric contour which the hair is forced to assume. The puffing of the hair at these points is also a consequence of the confining of the hair throughout a portion of its length to the concave face of the arm A by the arm B as the puffing occurs where the hair is not so confined.

While the arm B is shown as bowed longitudinally, it is obvious that when a lock of hair is wrapped around the arm A and the arm B sprung in the closed position, this arm B will be flexed into a substantially straight member and thereby confine the arm to the concave face of the member A throughout its entire length. After the hair has remained in the curler the prescribed length of time the curler is opened and the hair slipped off the arm A. The hair will then be in the curly or waved state desired.

110

Having thus described my invention what I claim is:

1. A hair curler formed in two sections and comprising a rigid concavo-convex arm and a relatively narrow flat flexible arm, means hingedly connecting adjacent ends of the arms, the flexible arm bearing against the concave face of the concavo-convex arm and being so disposed as to cause the hair which is adapted to be wrapped about the concavo-convex member to lie adjacent the concave face thereof, and means for connecting the free ends of the arms when they are sprung toward each other.
- 15 2. A hair curler formed in two sections and comprising a rigid concavo-convex arm and a longitudinally bowed relatively narrow flexible arm, means hingedly connecting one adjacent end of each of the arms, the flexible arm being of less width than the concavo-convex arm and bearing against the concave face thereof so as to cause the hair which is adapted to be wrapped about the concavo-convex member to be confined against the concaved face thereof and means for connecting the free ends of the arms together when they are sprung toward each other.
- 20 3. In a hair curler the combination with a rigid concavo-convex arm of a relatively narrow flat flexible arm, said narrow arm being of such width as to permit the same to be partially housed within said rigid arm when the two arms are in a closed position and means for connecting the free ends of

the arms together when they are sprung toward each other.

4. In a hair curler the combination with a rigid concavo-convex arm of a relatively narrow flat flexible arm, said narrow arm 40 being of such width as to cause the hair which is wrapped about the concavo-convex arm to follow the concave face of the rigid arm the hair being retained against the convex face of the rigid arm because of the 45 tension imparted thereto by the clamping action between the flexible arm and the concave face of the rigid arm and means for connecting the free ends of the arms together when they are sprung toward each 50 other.

5. A hair curler formed in two sections and comprising a rigid concavo-convex arm and a relatively narrow flat flexible arm, means hingedly connecting the adjacent ends of the arms, the concavo-convex arm being adapted to have wrapped thereon the hair, the hair following the convex face and spanning the concaved face thereof, the flexible arm when the arms are 60 sprung toward each other being disposed adjacent the concave face of the rigid arm, causing the hair which spans the concaved face to be stretched and forced against the concaved face of the concavo-convex arm 65 and means for connecting the free ends of the arm when they are sprung toward each other.

ROBBIE GORDONE.
